UNITED STATES PATENT OFFICE.

WALTER LEE BEARD, OF WILBURTON, OKLAHOMA.

FOLDABLE TREAD AND RISER FOR CAR-STEPS.

1,241,078.

Specification of Letters Patent. Patented Sept. 25, 1917.

Application filed June 22, 1917. Serial No. 176,332.

To all whom it may concern:

Be it known that I, WALTER L. BEARD, a citizen of the United States, residing at Wilburton, in the county of Okmulgee, State 5 of Oklahoma, have invented a new and useful Foldable Tread and Riser for Car-Steps; and I do hereby declare the following to be a full, clear, and exact description of the invention, such as will enable others 10 skilled in the art to which it appertains to make and use the same.

This invention relates to the lower step of cars, and an object of the invention is to provide a device of this kind, in which 15 the tread and riser thereof are foldable beneath the lower rigid step.

Another object of the invention is the provision of operating means including a rocking shaft, provided with gear and link 20 connections with the tread, whereby, when said shaft is rocked by means of a handle and the action of a spring, the tread and riser of the foldable step are collapsed beneath the lower rigid step of the car.

In practical fields, the details of construction 25 may necessitate alterations falling within the scope of what is claimed.

The invention comprises further features and combination of parts, as hereinafter 30 set forth, shown in the drawings and claimed.

In the drawings:—

Figure 1 is a view in elevation of a portion 35 of one end of a car, showing the tread and the riser of a foldable step as collapsed beneath the lower rigid step, and also illustrating the means for operating such foldable parts.

Fig. 2 is also a view in elevation of a portion 40 of one end of the car, showing the foldable tread and riser extended into positions to be used.

Fig. 3 is a view in side elevation of the car steps, showing the foldable tread and 45 riser extended.

Fig. 4 is a plan view of a lever device for actuating the rock shaft, also showing the segment for the lever, which is attached to a portion of the car which is shown in section.

Fig. 5 is an edge view of the means for operating the rock shaft, showing parts thereof in section.

Referring more especially to the drawings, 50 1 designates the body of a car, only a portion of which is shown, and 2 the

steps thereof, which form a part of the car rigidly, and 3 denotes the side pieces of the steps.

Secured by screws 4 to the outer faces 60 of the sides 3 adjacent the lower outer portion thereof are T-shaped plates or members 5. Mounted in the arms 6 of said plates or members 5, is a suitable pivot rod 7, and secured by screws 8 to the end edges 65 of the riser 9 of the foldable step, are the straps 10. The pivot rod 7 extends through the upper ends of the straps 10 and through the riser 9, adjacent its upper edge, 70 whereby said riser is pivotally mounted. By means of the straps 10 the riser 9 is reinforced, particularly where the rod 7 passes through the riser, thereby preventing 75 the upper edge portion of the riser from severing or otherwise becoming split or broken, incident to the strain on the riser. Secured by screws 11 to the end edges of the tread 12 of the foldable car step, are the reinforcing straps 13. Rising upwardly 80 from the upper edges of the straps 13, adjacent their inner ends are ears or lugs 14, and through which, and the lower ends of the straps 10, and also through the riser 9, is a pivot rod 15, thereby pivotally connecting 85 the tread to the riser. It is to be observed that the straps 10 also reinforce the lower portion of the riser, in the same manner that the upper part of the riser is reinforced. The inner ends of the straps 13 merge 90 integrally into the links 16, which extend upwardly and inwardly substantially on an angle in parallelism with the angular disposition of the rigid car steps.

Secured by any suitable means, preferably bolts 17, to the inner face of one of the uppermost risers of the rigid car steps are bearings 18, in which a rock shaft 19 is mounted. Fastened by pins 20 to the opposite ends of the shaft 19, are arms or levers 21. Splined by means of a feather 95 22 to the central portion of the shaft 19, is an arm or lever 23, and connected to the lower end of said arm, is a spring 24, the upper end of which is connected to an eye 25 of the under face of the uppermost tread 100 of the car steps. Also on one end of the shaft 19 is a beveled gear 26 which meshes with the beveled gear 27 on the lower end of a shaft 28, which is disposed vertically, 105 and mounted in bearings 29 of the inner face of the vestibule dash or wall 30. Fastened by pins 31 on the shaft 28 one above

and one below the uppermost tread of the car steps are collars 32, acting to prevent axial movement of the rockshaft 28. Made fast by means of a pin 33 to the upper end 5 of the rock shaft 28 is a handle 34. Pivoted at 35 on the handle is a lever 36, which is under tension of the spring 37 (which is interposed between the lever 36 and the handle) in order to keep the dog 38 (which 10 is pivoted to the inner end of said lever 36) protruding through the handle, whereby the nose of the dog may engage either of the notches 39 and 40 to hold the handle in adjusted positions. The notches 39 15 and 40 are constructed on the segment bar 41, which is concentric with said shaft 28 and is secured at 42 to the inner face of dash 30 of the vestibule of the car. Normally the tread and the riser 12 and 9 of the 20 foldable car step are folded beneath the lowermost rigid steps, and when such foldable parts are in such positions, the nose of the dog engages the notch 40, and the handle is disposed laterally of the dash 30, as 25 shown in Fig. 1 clearly, when collapsing the tread and the riser, the spring 24 assists materially, in fact, substantially automatically folds said step. When it is desired to extend the tread and riser, the 30 outer end of the lever 36 is depressed, disengaging the nose of the dog from the notch 40, whereupon the handle is free to be moved. When the handle is moved from the position shown in Fig. 1 to that shown 35 in Fig. 2, movements are imparted to the shafts 28 and 19, the shaft 19 rocking against the action of the spring 24, lowers or extends the tread and the riser, by virtue of swinging the levers or arms 21. 40 When the handle reaches the position shown in Fig. 2, the nose of the dog is allowed to immediately engage the notch 39 thereby holding the foldable step lowered.

The invention having been set forth, what 45 is claimed as new and useful is:—

1. In combination with the rigid steps of a car, a tread and a riser of a car step

pivotedly united, said riser having pivotal connections with the outer portion of the lowermost rigid step, whereby said tread and riser may collapse beneath the lower rigid step, said tread having inwardly and upwardly inclined rigid links, a rock shaft mounted in bearings of the upper inner portion of the rigid car steps provided with levers adjacent its opposite ends pivotally connected to the inner upper ends of the links, an additional lever on said shaft, a spring having one end connected to the rigid car step and its other end to the additional lever, and means having gear connections with said rock shaft for imparting movement thereto to lower the tread and riser against the action of said spring.

2. In combination with a set of rigid car steps, T-shaped plates secured to the opposite sides of the lowermost rigid step, a foldable car step comprising a tread and a riser, the end edges of the riser having reinforcing metal straps, a pivot rod extending through said straps, said T-shaped plates and through the upper edge portion of the riser, thereby pivotally uniting said parts, metallic straps secured to the end edges of the tread, and having their inner ends provided with upwardly extending lugs, a pivot rod extending through the lugs and the lower ends of the reinforcing straps and the lower edge portion of the riser, thereby pivotally uniting the riser and the tread, said metallic straps of the tread merging integrally into inwardly and outwardly inclined links to be actuated for collapsing the tread and the riser beneath the lowermost tread of the rigid steps, and means connected to the inner upper ends of the links for actuating the same.

In testimony whereof I have signed my name to this specification in the presence of two subscribing witnesses.

WALTER LEE BEARD.
